UNITED STATES PATENT OFFICE.

EDWIN G. STAUDE, OF MINNEAPOLIS, MINNESOTA, ASSIGNEE, BY MESNE ASSIGNMENTS, TO UNITED STATES ENVELOPE COMPANY, OF SPRINGFIELD, MASSACHUSETTS, A CORPORATION.

GLUING-ROLL.

1,193,628.

Specification of Letters Patent. Patented Aug. 8, 1916.

Application filed February 14, 1913. Serial No. 748,346.

To all whom it may concern:

Be it known that I, EDWIN G. STAUDE, a citizen of the United States, resident of Minneapolis, Hennepin county, Minnesota, have invented certain new and useful Improvements in Gluing-Rolls, of which the following is a specification.

My invention relates to means for applying glue to the surface of a blank or other article.

The object of the invention is to provide a gluing means capable of rapid, convenient adjustment to adapt it for gluing surfaces of varying sizes and shapes.

A further object is to provide means for evenly distributing the glue without smearing and without using a greater quantity of glue than necessary for the blank surface.

A further object is to provide a gluing means adapted for applying glue to surfaces generally, but particularly adapted for gluing the flaps of envelop blanks.

My invention consists generally in various constructions and combinations, all as hereinafter described and particularly pointed out in the claims.

In the accompanying drawings forming part of this specification, Figure 1 is a plan view of a sectional gluing roll embodying my invention, Fig. 2 is a sectional view, showing the preferred means for mounting the sections of the roll on a shaft, Fig. 3 is an end view of the roll, Fig. 4 is a perspective view of a portion of the roll, with the shaft removed, illustrating the manner of adjusting the roll segments, Fig. 5 is a plan view of a gluing roll showing a modified construction, Fig. 6 is a sectional view of the same, Fig. 7 is an end view of the modified construction, Fig. 8 is an end view, showing another modification in the construction of the roll, Fig. 9 is a plan view of the modified construction shown in Fig. 8, Fig. 10 is a detail view, showing the manner of mounting the gluing points of Fig. 1 in the edges of the segments, Fig. 11 is a detail sectional view, showing the preferred manner of mounting the gluing surfaces of the modification shown in Fig. 8, in the surfaces of the quadrants shown in said figure.

In the drawings, 2 represents a shaft.

3 is a key adapted to slide in a way 4 formed in the shaft 2 and 5 is a sleeve that is secured to the key 3 by any suitable means, such as the screw 6. 7 is a set screw mount-

ed in said sleeve and engaging the key 3 to lock the sleeve securely on the shaft. The screw 6 secures the sleeve 5 to the key 3, while the set screw 7 carried by said sleeve bears against the other end of said key to 60 press the same firmly against the bottom of the way 4, thereby to maintain the sleeve and key in the desired position of longitudinal adjustment on the shaft. One end of the sleeve 5 is preferably provided with an 65 annular flange 8 and the opposite end of the sleeve is threaded to receive a lock nut 9. Between this flange and lock nut I provide a series of roll sections or segments 10 having hubs 11 provided with rabbeted edges 12 70 to allow the hubs to nest or interlock with one another on the sleeve 5. The hubs operate to hold the segments in place on the sleeve and allow them to be rotated for the different adjustments of the gluing surfaces. 75 The ends of the segments are adapted to lap by one another, as indicated in Fig. 4, to allow their rotary adjustment on the sleeve, and each segment is provided with a socket 13 therein adapted to receive a gluing point 80 or plug 14 which projects slightly beyond the peripheral surface of its segment and is adapted to receive glue from any suitable means for application to a blank and particularly to the flap of an envelop blank. 85 These gluing points or surfaces are preferably arranged as indicated in Fig. 1, in diverging rows, running crosswise of the segments to adapt them for the application of glue to the triangular section of a blank, 90 such as the flap of an envelop. The segments are preferably provided with curved slots 15 to receive clamping bolts 16 by means of which the segments may be held in their locked relation. Each set or group 95 of segments has a locking bolt and by loosening one of the bolts the segments secured together by that bolt may be adjusted with respect to the corresponding segments, which are locked together by the other bolt, the curved slots 15 being of sufficient length to allow the required degree of rotary adjustment. I am thus able to quickly adjust the points or gluing surfaces of one row toward or from the corresponding points of the other row and thereby adapt the gluing roll for varying angles of the edges to be glued, and in the case of envelops, for different lengths of flaps and different shapes thereof.

100

105

110

The gluing points may be made of any suitable material, preferably rubber, and will apply the glue in the desired quantity upon a surface, such as the edge of a blank 5 or an envelop flap.

In Figs. 5 and 6 I have shown a modified construction of the gluing roll, consisting of a hub 17 mounted on a shaft 18 in substantially the same manner as described 10 with reference to Figs. 1 and 2, said hub being provided with an annular flange 19 between which and a clamping plate 20, secured to the other end of the hub by screws 21, a series of segments 22 are arranged. 15 These segments are also arranged in groups, as in the construction above described, with a space provided between the adjacent ends of the groups, and this space is preferably bridged by a series of rings 23 arranged between the abutting edges of the segments 20 and extending entirely around the hub, being held thereon by the pressure of the segments upon one another. Upon loosening the screws 21, the pressure on the segments 25 will be relieved and they may be adjusted endwise between the rings to adapt the gluing points, corresponding to those described in the preferred construction, to the varying shapes and angles of the surfaces or 30 flaps to which the glue is to be applied. The outer segments are preferably made wider at the base to enter recesses 24 formed in the flange 19 and the clamping plate 20.

In Figs. 8 and 9 I have shown another 35 modification in the construction of the gluing device, which consists in a pair of quadrants 25 having hub sections 26 clamped on a shaft 27 by means of a clamping screw 28. The faces of these quadrants 40 are each provided with a series of diagonally arranged parallel grooves 29 which are dovetailed in form and each provided with a slide 30 having beveled edges to fit the walls of the groove. A gluing block 31 is 45 seated upon the quadrant over each groove therein and is held in place by means of a clamping screw 32 which passes through the block and is tapped into the slide 30. When this screw is tightened, the block 31 will be 50 locked firmly on the surface of the quadrant and when the screw is loosened the block with the slide 30 may be moved back and forth in its groove toward or from the corresponding block on the other quadrant. 55 The head of the screw is preferably flush with the surface of the block and forms therewith a gluing surface or point which, when supplied with glue, is adapted to apply it to a blank such as the flap of an envelop 60 or wherever it is desired to apply glue to a surface. As indicated in Fig. 9, this construction of the gluing device provides for a wide range of adjustment of the gluing surfaces for I may adjust the blocks 31 so that those of one quadrant will be in line

with the blocks of the other quadrant or at any desired angle thereto, or I may arrange the blocks of one quadrant in parallel relation with those of the other quadrant, and thus adapt the gluing device for blanks of any shape and size. 70

The angular arrangement of the gluing points or surfaces, as shown in the drawings, adapts the device particularly for applying glue to the triangular flaps of envelop blanks, but I do not confine myself to this use, as the device may be used wherever it is desired to apply glue to surfaces or to the edges of blanks, particularly where relative adjustment of the gluing points is desirable to meet the varying shapes and sizes of the blanks to be glued. 75

It is particularly to be noted that the first described form of my invention provides opposing series of adjustable peripherally disposed gumming members; the adjustment of any member of either series increases or decreases its distance, measured peripherally, from the corresponding member of the other series, without moving said member out of the plane, transverse to the axis of the roll, which it occupies in common with the corresponding member of the other series. 80

I claim as my invention:—

1. In a gluing roll, opposing series of peripherally disposed gumming members, with the corresponding opposed members of each series in planes transverse to the axis of the roll, and means for adjusting the members of each series relatively to each other and to the corresponding members of the other series. 100

2. A device of the character described, comprising roll segments, and opposing series of peripherally disposed gluing points mounted on said roll segments, the gluing points of each series being relatively adjustable with respect to those of the same series and with respect to the corresponding points of the opposing series. 105

3. A gluing roll comprising roll segments arranged in groups, the segments of each group having curved slots therein and bolts securing the segments of the same group together, the segments of each group being capable of adjustment with respect to one another and with respect to the segments of the other group, said segments having peripheral gluing surfaces. 115

4. A gluing roll comprising a series of roll segments arranged in groups, the segments of one group having their endslapping by the adjacent segments of the other group and capable of rotary adjustment with respect to one another, said segments having peripheral gluing surfaces. 120

5. A gluing roll, comprising opposing series of segments, with the corresponding opposed segments of each series in planes 125

transverse to the axis of said roll, a hub on which said segments are angularly adjustable, and gumming members disposed on the peripheries of said segments.

6. A gluing roll comprising a series of roll segments having hubs and a shaft whereon said hubs and segments are capable of rotary adjustment, said segments being arranged in groups, the segments of one

group having their ends lapping by the adjacent segments of the other group and each group of segments having peripheral gluing points.

7. A gluing roll comprising a series of roll segments and hubs therefor, and a shaft whereon said hubs are capable of rotary adjustment with said segments, means for locking said hubs and segments on said shaft, said segments being arranged in

groups, each group of segments having curved slots therein, and locking bolts securing the segments of the same group together, the abutting ends of the segments of the groups lapping by one another, the segments of each group being capable of adjustment with respect to one another and with respect to the segments of the other group, and gluing points provided in the peripheries of said segments.

8. A gluing roll comprising a series of

segments arranged in groups, means for locking all the segments together and means for locking the segments of one group independently of those of the other group, said segments, when loosened, being capable of rotary adjustment and provided with gluing points in their peripheral surfaces.

9. A gluing roll comprising a shaft, a sleeve mounted thereon having an annular flange at one end, a series of segments mounted for rotary adjustment on said sleeve, a clamping plate between which and said flange said segments are gripped and held, said segments being provided with peripheral gluing surfaces.

10. In a device of the character described, a plurality of roll segments, peripheral gluing points arranged thereon in opposing groups, with the corresponding opposed points of said groups in planes transverse to the axis of said segments, and means for changing the peripheral distance of each point of either group from the corresponding point of the other group.

In witness whereof, I have hereunto set my hand this 4th day of February, 1913.

EDWIN G. STAUDE.
